UNITED STATES PATENT OFFICE.

ALBERT N. PETERS, OF GALENA, MISSOURI.

WATER COOLING AND DISTRIBUTING APPARATUS.

1,206,241.

Specification of Letters Patent. Patented Nov. 28, 1916.

Application filed August 14, 1915. Serial No. 45,574.

To all whom it may concern:

Be it known that I, ALBERT N. PETERS, residing at Galena, in the county of Stone and State of Missouri, have invented a new 5 and Improved Water Cooling and Distributing Apparatus, of which the following is a specification.

This invention has reference to that class of water distributing apparatus in which 10 are included a reservoir, a cooling tank co-operatively connected with the reservoir and in such a manner that a continuous circulation of the water within the reservoir and the cooling tank may be maintained 15 when the temperature of the water in the reservoir drops below the temperature of the water in the cooling tank, and in which the water may be drawn off either directly from the reservoir or from the cooling tank.

20 In its more complete nature, my invention comprehends an improved apparatus in which means are included for applying pressure to the water held in the cooling tank when the water level in the said tank drops below the delivery pipe, and in which the cooled water may be used in connection with a milk house and for constantly supplying one or more stock troughs.

With other objects in view that will be 30 hereinafter referred to, my invention is an improved apparatus that embodies the peculiar and novel arrangement of the parts hereinafter fully explained, specifically pointed out in the claim and illustrated in the accompanying drawing, in which:

Figure 1 illustrates diagrammatically, in vertical elevation, my improved apparatus. Fig. 2 is a similar view of a modified arrangement of my apparatus hereinafter 40 specifically referred to. Fig. 3 illustrates diagrammatically, in vertical elevation, a further modification of my improved apparatus hereinafter explained.

45 In the practical application of my invention, and in the simplest form thereof, as illustrated by Fig. 1, of the drawing, a double tank system is shown, which comprises an upper tank or reservoir 1 suitably 50 located adjacent the roof of the dwelling to receive the rain water which in passing from the roof 2 flows into a pipe 3 of a filter 4 provided with a valved outflow 5 at the lower end and whose upper end has a discharge that connects with the upper end of 55 the reservoir, as shown, and the said filter

4 may also be fed with water pumped from a spring or well.

Reservoir 1, which may be of any desired shape and built up of any material, has an 60 outflow or circulating pipe 8 that extends down and connects with a lower or cooling tank 7, in practice sunk in the ground below the normal freezing point, and the said tank is also connected with the reservoir 65 through a return pipe 6 which, as also the pipe 8, has a control valve 80.

An outlet pipe 9 leads from the bottom of the cooling tank 7 within the dwelling and as shown has its valved end 90 located 70 over a sink 10.

It is understood in the practical application of my invention, a number of outlet pipes may lead from the cooling tank 7 for service at any height within the dwelling 75 below that of the base of the reservoir.

By reason of arranging the reservoir 1, the cooling tank 7 and connecting the said reservoir and tank by an outflow and a return pipe, as shown and described, assuming 80 the valves in the said two pipes that extend down from the reservoir, are open, it is evident that so long as there is any water in the reservoir 1, the water contained therein will force the water from the cooling 85 tank when the valve on any one of the outlet pipes from the cooling tank is open, out through the said opened outlet pipe, it being also understood that since warm water is lighter than cold water, it makes no difference in my apparatus how hot the water in the reservoir 1 may get, it will not affect the water in the cooling tank until the water is drawn from the said cooling tank, and then it will remain at the top of the 90 cooling tank and generally have time to cool before being drawn out of the said cooling tank. Water, may if desired, be drawn off directly from the reservoir 1 through a valved pipe 12 that joins with the pipe 6 100 and leads into the dwelling as shown.

13 designates an air pump connected with the house end of the pipe 12 for forcing the water in the cooling tank up into the house when the reservoir 1 is empty.

105 Instead of mounting the reservoir in the manner shown in Fig. 1, the said reservoir may be mounted on a concrete milk-house to provide for effectively keeping the milk cooling trough 14 filled with cold water, fed from a valved outlet pipe 15 that extends up from the cooling tank, for keeping the

milk and other articles set in the trough, cool.

16 designates an outlet pipe for leading off the warmed water in the milk trough to 5 a feeder in the poultry or stock yard, and 17 is a pipe that leads the water direct from the reservoir into the milk trough.

18 indicates a pipe joined with the cooling tank that leads to a stock trough 19 provided with the usual float valve 20 for automatically controlling the flow of the cold water into the said trough.

By reason of the manner in which the upper and lower tanks are connected when 15 in cold weather the water in the reservoir is cooled below the temperature of the water in the cooling tank the said water gravitates to the bottom of the cooling tank and thereby forces the water within said cooling tank 20 back up into the reservoir, and such water circulation tends to prevent the water in the reservoir from freezing in extreme cold weather and to further protect the reservoir tank from strain in case of possible freezing, 25 a number of wooden bars 25 are pendently supported from the top of the tank and within the water, about which, in case of freezing the ice will form, and thereby take the strain off the tank.

30 When the demand is very great on the cooling tank that is in direct connection with the reservoir (the main cooling tank)

and especially where some of the water is to be delivered at a considerable distance from the main cooling tank, then water can be best delivered cool by putting in another or additional cooling tank 30 that joins with the main delivery pipe through a pipe connection 31, as is clearly shown in Fig. 3. By providing a second cooling tank, as 40 stated, a person living at a considerable distance from the main reservoir may have a water system as good as one living adjacent to the said main reservoir.

From the foregoing description taken in 45 connection with the accompanying drawing, the complete arrangement of my cistern system, the manner in which it operates and its advantages will be readily apparent.

What I claim is:

In a water distributing apparatus, the combination with a source supplying water, a reservoir elevated above the level at which the water is to be distributed and into which the water is delivered from the said source 55 of supply; of a cooling tank located in the ground below the normal freezing point, a lead pipe and a return pipe connecting the bottom of the reservoir with the top of the cooling tank, and a valved outflow pipe that 60 extends from the lower end of the cooling tank to a point of delivery.

ALBERT N. PETERS.
